CHARLES BOOZ, OF BUFFALO, NEW YORK, ASSIGNOR TO HENRY M. BIRGE,

DESIGN FOR WALL-PAPER.

SPECIFICATION forming part of Design No. 26,091, dated September 22, 1896.
Application filed August 5, 1896. Serial No. 601,826. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of a series of vertical stripes formed of flowers and leaves, ribbons, and emblems, with figures of the "Watteau" style placed in oval frames with flowers and leaves and arranged at certain distances apart on said vertical stripes, as represented in the accompanying drawings.

15 The border for the said design is formed of similar emblems and figures of the Watteau style, inclosed in an oval frame sur-

rounded with flowers and leaves, and bows of 20 ribbon above and below said oval frame, and a flowing ribbon forming an open panel around the oval frame and connected by sprays of flowers and leaves, as shown in the drawing. An ornamental band forms the 25 bottom of the border, as shown.

What I claim is—

1. The design for wall-paper herein shown and described.
2. In the design for wall-paper, the border 30 herein shown and described.

Witness my hand this 1st day of August, 1896.

CHARLES BOOZ.
